John S. Jones

ATTORNEY.

UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION.

LOOSE-LEAF BINDER.

Application filed June 2, 1924. Serial No. 717,424.

To all whom it may concern:

Be it known that I, RICHARD M. VAN VALKENBURGH, a citizen of the United States, residing at Kansas City, in the 5 county of Jackson and State of Missouri, have invented certain new and useful Improvements in Loose-Leaf Binders, of which the following is a complete specification.

The present invention relates to improvements 10 in loose-leaf binders, and the invention has for its general object to provide means for securing a positive retaining of the leaves within said binder when same is not in actual use and subject to such falls or 15 blows as are likely to dislodge and scatter the sheets.

It is well known in this art, that loose-leaf binder leaves having punchings open to 20 the edge free themselves from the binder's grip when the same is dropped or jolted. This invention contemplates simple means for overcoming this inconvenience and has for its object the provision of a special 25 punching in the binder leaf which co-operates with removable retaining means, held in engagement by the binder members, but which does not interfere with the removal or transfer of said leaves from the binder during its use.

30 A further object of this invention is the provision of a leaf having a special punching for allowing an expansible post to be positioned in engagement with the binder members without removing the entire contents of 35 the binder from the leaf holding posts or even forcing the leaves out of their proper position in any way.

The invention further makes provision 40 for the use of this safety feature with any style of loose-leaf binder.

With the foregoing and other objects in view, the invention will be more fully described hereinafter, and will be more particularly pointed out in the claims appended 45 hereto.

In the drawings, wherein like symbols refer to like or corresponding parts throughout the several views,

Figure 1 is a vertical fragmentary section 50 through an expansible back binder showing the special leaf punching in cross section and the retaining post being inserted.

Fig. 2 is a similar view with the binder closed and the retaining post in position.

55 Fig. 3 is a corresponding section showing

the invention in connection with a tubular binder member and open back loose-leaf binder.

Fig. 4 is a detail sectional view taken along line IV-IV of Fig. 2 showing the 60 slotted leaf without the retaining post.

Referring more particularly to the drawings, wherein 6 is an ordinary loose-leaf binder of either open or expansible back type having hinged covers 7 and posts 8. 65 Binder members 9 may be either solid or hollow and, in both instances, are provided with sockets 10, which are preferably centrally located with reference to the ends of members 9, and are in alinement with 70 posts 8, and extend but part way through said members 9.

An expansion post 11 of the ordinary type including male member 12, female member 13 and compression spring 14 is 75 preferably used to engage sockets 10, as shown in Fig. 2, and retain the leaves of the binder in position in the event of a fall or sudden blow which would ordinarily dislodge the leaves from the gripped engagement between members 9. This construction also prevents unauthorized persons and those not holding the key, in the case of key 80 operated binders, from removing the leaves without tearing.

To carry out this desirable feature, the invention further contemplates the use of a specially punched leaf 15 which is provided with an elongated opening 16 punched to align with the sockets 10 of binder members 90 9 when leaves 15 engage posts 8 with notches 17, as clearly shown in Fig. 4.

The elongated opening 16 is of uniform 95 width, lies at right angles to the binding edge of the leaf 15, and is slightly spaced from it to provide an engagement for the expansion post.

Operation.

When the binder is in actual use, the expansion post is removed. In replacing the leaf retaining means, the leaves are arranged in engagement with posts 8, as illustrated in Fig. 4, the expansion post passed down through elongated openings 16, as shown in 105 Fig. 1, male member 12 pressed downwardly and inwardly and snapped into socket 10 of the upper binder member 9. The binder is then pressed together and locked as shown in Fig. 2. This related construction of leaf 110

and binder also permits the removal and replacing of leaves, having open punchings, in open back, sectional post binders without removing the covers entirely off the posts.

5 It is obvious that various changes and modifications may be made in details of construction of the above specifically described embodiment of this invention without departing from the spirit thereof, such 10 changes and modifications being restricted only by the scope of the following claims.

What is claimed is:

1. In combination with a loose-leaf binder having an expansible back supporting a pair 15 of binder members, leaf holding posts carried by said members and an expansion post adapted to be positioned in sockets formed in each binder member, a plurality of sheets removably engaging said leaf holding posts 20 each having means allowing the positioning of said expansible post in said sockets while said leaves are in the post engaging position.

2. In combination with a loose-leaf binder 25 having an expansible back supporting a pair of binder members, leaf holding posts carried by said members and an expansion post adapted to be positioned in sockets formed 30 in each binder member, a plurality of sheets removably engaging said leaf holding posts having means for allowing said expansion post to be positioned in said sockets while 35 said leaves are in the post engaging position, comprising an elongated opening having the long axis thereof at right angles to the binding edge thereof, in vertical alinement with said sockets and spaced inwardly from said binding edge.

3. A loose-leaf binder comprising in com-

bination, a pair of binder members each 40 having a socket formed therein intermediate its ends, leaf holding posts supported by said binder members, a plurality of leaves provided with openings along one edge for removably engaging said posts and an elongated opening in vertical alinement with the sockets in each binder member whereby an expansion post may be positioned in said sockets without removing the binder members from said leaf holding posts. 45 50

4. A loose-leaf binder comprising in combination, a pair of binder members each having a socket formed therein intermediate its ends, a telescoping back joining said members to maintain the same in spaced vertical alinement, telescoping leaf holding posts supported by said binder members, a plurality of leaves provided with openings along one edge for removably engaging said posts and an elongated opening having the 55 long axis thereof at right angles to the binding edge of the sheet in vertical alinement with said sockets and spaced inwardly from said binding edge whereby an expansion post may be positioned in said sockets to 60 hold the sheets against removal from said binder. 65

5. In combination with a loose-leaf binder provided with a socketed binder member, a filler leaf having an elongated opening of 70 uniform width adjacent the binding edge thereof, whereby an expansion post may be positioned in said socket without disassembling said binder.

In testimony whereof I hereunto affix my 75 signature this 29th day of May, 1924.

RICHARD M. VAN VALKENBURGH.
